UNITED STATES PATENT OFFICE.

GEORGE B. BURCH, OF NEW YORK, N. Y., ASSIGNOR TO LESLIE STEVENS, OF GLEN RIDGE, NEW JERSEY.

PHONOGRAPH REPRODUCER.

1,414,803.

Specification of Letters Patent. Patented May 2, 1922.

Application filed April 3, 1918, Serial No. 226,382. Renewed August 2, 1921. Serial No. 439,199.

To all whom it may concern:

Be it known that I, GEORGE B. BURCH, a citizen of the United States, and a resident of the city of New York, county of Kings, 5 and State of New York, have invented new and useful Improvements in Phonograph Reproducers, of which the following is a specification.

The invention relates to phonograph 10 producers, and more particularly to improvements in means for vibrating the sound reproducing diaphragm, and the invention aims to provide such means which shall be simple in construction, durable, and highly 15 efficient in transmitting vibrations from the record to the diaphragm so that a very perfect reproduction of the recorded sounds may be secured. These, and further objects 20 are accomplished by my invention, one embodiment of which is hereinafter more particularly set forth.

For a more particular description of my invention, reference is to be had to the accompanying drawing, forming a part here- 25 of, in which—

Fig. 1 is a sectional view of a phonograph having a reproducer embodying my invention.

Fig. 2 is an enlarged sectional view of a 30 portion of the diaphragm, stylus holder, transmission rod and connected parts.

Fig. 3 is a sectional view, taken on the line 3—3 of Fig. 2, looking in the direction of the arrows.

Fig. 4 is a plan view of a disk, which supports one end of the transmission rod.

Throughout the various views of the drawings, similar reference characters designate similar parts.

The drawings show a phonograph 1 provided with a suitable casing 2, in which is contained a motor 3, of any suitable kind. Rising from this motor is a vertically disposed shaft 4 on which a rotating turntable 5 is mounted in the conventional manner, and this table supports a record 6. A bracket 7 adjacent to the turntable 5 and at one side thereof carries a swivel pin 8 which turns freely therein, and at the top of this

50 pin is a hinge 9 connected to rings 10, which have a diaphragm 11 fixed between them. In the preferred embodiment of my invention, this diaphragm is made large, that is about a foot in diameter, but may be more 55 or less, as desired, and may be thickened at

its center by being made of several layers, or otherwise, and is convex in form when viewed from its upper surface, and concave when viewed from its lower, being most desirably of convex conoidal form, as shown, 60 and having a gutter or trough 12 adjacent its edge between the main portion of the diaphragm and an edge flange by which it is secured to the supporting rings 10. Sound vibrations transmitted to the center of this 65 diaphragm set the diaphragm in vibration, and the diaphragm being permitted by its relatively flexible edge formation to vibrate freely, the whole diaphragm acts to set up sound waves in the surrounding or adjacent 70 atmosphere so that no megaphone or other amplifying horn, or similar device, is required.

The rings 10 are connected by screws 13 and washers 14 to a spider 15 which holds a 75 tube 16, and in this tube are mounted various parts, one of which is a transmission rod 17 which has its upper end firmly fixed to the diaphragm 11, at the center of the dia- 80 phragm, and near its lower end it is hori- zontally disposed, as shown at 18, in Fig. 2, then bent abruptly so as not to touch the cylinder 16, and then it runs straight, but diagonally, up to a point near the top of the tube 16, and from thence it is again bent 85 slightly so as to run in and about the axis of the diaphragm to which it is secured. Beyond the part 18, and at the lower end of this transmission rod, it is screw-threaded and made to run in and about the axis above re- 90 ferred to, or substantially this axis, and it is held in place by means of the perforated disk 19 which is shown in Fig. 4. This disk 19 is fixed in the lower end of the tube 16 between the nuts 20 and 21, as shown in 95 Fig. 2.

The transmission rod 17 extends through a central perforation in the disk 19 and is secured to the disk by a nut 22 on the inner side of the disk and the needle, or stylus, 100 holder 23 on the other side of the disk. The stylus holder 23 carries a needle, or stylus, 24, which is secured by a set screw 25, in the conventional manner.

The disk 19 is of peculiar construction, 105 and its thickness will vary from twelve to twenty-five thousandths of an inch accord- ing to the diameter of the rod 17, the thicker the rod the thicker the disk. The disk may be made in several forms, but the preferred 110

form is shown where there is a central perforation 26 which is surrounded by a horseshoe opening 27, substantially as shown, and the neck 28. The width of this neck 28 is 5 important, because it should be proportionate to the diameter of the rod 17, so that this rod will have a free vibration, but not too free, when the apparatus is in use. The relative positions of the neck 28 and 10 the part 18 of the transmission rod 17 must be as shown. When a record having a lateral cut groove is used these parts must be placed in a plane at right angles to the direction of this groove. If the groove be one 15 of varying depth, these parts are placed at right angles to the position just described. In view of the foregoing, the operation of my improved phonograph will be readily understood. Assuming that the machine is 20 in operation in the conventional manner, and the stylus 24 rests on a suitable record 6, which may be one with a lateral cut groove or one with a vertical cut groove, according to the nature of the disk, all disks being the 25 same to this instrument without regard to the nature of the thread, in any event, the sound vibrations are gathered by the stylus 24 and transmitted through the stylus holder 23 to the transmission rod 17 and 30 amplified by the bent laterally disposed portion 18 of this rod, with the result that a very perfect transmission to the diaphragm of all the sound vibrations, regardless of nature or character, is obtained, and a loud, 35 clear and very perfect reproduction results. The exact form here shown of lateral extension 18 is not essential, although desirable, as this form may be any of several angles, all of which produce the desired result. The 40 point is that, while the transmission rod because of its being relatively very long and very slender is quite flexible, its short laterally bent portion adjacent the stylus holder will be sufficiently rigid so that, be- 45 cause of the rigidity of this laterally bent

part and the flexibility of the main part of the rod, vibrations of the stylus holder will be transmitted to the diaphragm in the direction of the length of the rod. The use of pivot pin connections with the possibility of lost motion is thus avoided and the resulting transmission of vibrations in the direction of the length of the connection between the stylus holder and the diaphragm is the same as though the connection were 50 to a rigid part of the stylus holder offset laterally from its pivotal axis. In the preferred embodiment of my invention this offset part 18 is over the neck 28, as shown in Figs. 2 and 3. 55

While I have shown and described one embodiment of my invention, it is obvious that it is not restricted thereto, but is broad enough to cover all structures that come within the scope of the annexed claims. 60

Having thus described my invention, what I claim is:

1. In a phonograph reproducer, the combination with a diaphragm, and supporting means therefor, of a stylus holder mounted 70 axially of the diaphragm and at a distance therefrom and capable of vibratory oscillation, and a long flexible transmission rod rigidly connected to the stylus holder and to the diaphragm and having a lateral bend 75 adjacent the stylus holder.

2. In a phonograph reproducer, the combination with a diaphragm, and supporting means therefor, of a stylus holder mounted axially of the diaphragm and at a distance 80 therefrom, the stylus holder being carried by a perforated thin disk peripherally supported from said supporting means in a plane transverse to the axis of the dia- 85 phragm and having a horseshoe opening ex- tending about its central supported portion, and a transmission connection extending from the stylus holder to the diaphragm.

GEORGE B. BURCH.
